Hanson & Hanson

UNITED STATES PATENT OFFICE

EDWARD GROVER DURNING, OF PHILADELPHIA, PENNSYLVANIA, ASSIGNEE TO THE
J. G. BRILL COMPANY, OF PHILADELPHIA, PENNSYLVANIA, A CORPORATION OF
PENNSYLVANIA

AXLE-BOX LID

Application filed February 19, 1929. Serial No. 341,166.

This invention relates to a journal or axle box lid, and is more particularly concerned with arranging a lid in such manner on the journal box that the lid is yieldingly urged 5 uniformly against the lips of said journal box.

An object of the invention is to devise an axle box having a lid urged uniformly thereagainst.

10 Another object is to produce a journal box having a lid yieldingly urged uniformly thereagainst.

Another object is to devise means for uniformly urging a lid against the lips of a journal box.

Still another object is to devise a journal box having a resilient spring mounted about the bolt pivotally securing the lid to the journal box, having a coiled spring mounted 20 about said bolt, and yieldingly engaging the lid to positively urge it against the lips of the journal box.

Other objects will appear hereinafter.

In the drawings which illustrate one example 25 of my invention,

Fig. 1 is a plan view of a journal box showing the journal box lid in position;

Fig. 2 is a vertical section taken on the line 2-2 of Fig. 1, while

30 Fig. 3 is a detailed illustration of the spring employed in my device.

At 1 is illustrated the usual form of journal box having vertical shoulders 2, and provided with a central aperture 3 for the reception 35 of the usual packing. The opening 4 to this aperture is closed by a suitable closure or lid 5 preferably provided with a tab 6 for actuation thereof, and also having a small central depression or aperture 7, forming a 40 catch for a purpose which will be described hereinafter.

The lid 5 is secured to the journal box 1 in any suitable manner as by means of a headed bolt 8, passing through an opening 9 formed 45 adjacent one end of said lid, and also passing through a corresponding opening 10 in a flange on one wall of the journal box 1. It is to be understood that the bolt may be adjustable, and is secured in position by any suitable type of washer 13. A cap 14 is carried

on said bolt and rests against the headed end thereof. This cap has an annular, inturned flange 15 adapted to retain a coiled spring 16 between the trough of said cap and the exterior of said lid to prevent binding between said spring and said bolt. A bushing 17 is mounted about the bolt and extends through the opening 9 in the lid, which is enlarged to accommodate it, to a point where it abuts against the outer face of the flange 11 on the journal box. The spring 16 carries at its inner end an elongated extension 18 which is bellied slightly upwardly in order to avoid contact with the lid 5 at points other than the approximate center thereof.

The extension 18 will thus be seen to bear against the lid of closure 5 at but a single, substantially central point, and to yieldingly urge the lid against the journal box in a substantially uniform manner, the force radiating uniformly in all directions from the point of contact with the lid. The pressure on the spring can be readily adjusted within predetermined limits by means of the lock nut 12. To insure a positive contact between the lid and the extension 18, said extension is provided with an inturned portion or lug 19 engaging with the previously described aperture or opening 17. When the spring is placed in position, the extension 18 will be secured in its proper position by merely locating the lug 19 in the aperture 7. This serves the further useful function of insuring a positive, non-sliding contact between the pressure means and the lid which results in unvarying, uniform contact between the lid 5 and the journal box 1.

It is of course understood that the invention is susceptible to numerous modifications and adaptations, and it is intended that it be limited only by the scope of the appended claims.

I claim:

1. A journal box having an opening 95 therein, a closure for said opening, said closure having a depression located substantially centrally thereof, means at one end of said closure for securing said journal box and said closure together in such manner as to permit pivotal movement of said closure in 100

its own general plane, and a coiled spring mounted about said means and having an extension with an inturned portion engaging said depression in said closure member, to 5 yieldingly urge said member uniformly against said journal box.

2. In a journal box having an opening, a lid closing said opening, a headed bolt pivotally securing said lid at one end to said journal 10 box, and a coiled spring mounted between said headed end of the bolt and said lid and having an extension bearing substantially centrally against the exterior of said lid to urge it uniformly against the said journal 15 box.

3. In a journal box having an opening therein, a closure member therefor, a bolt pivotally securing one end of said lid to said journal box, a coiled spring around said bolt, 20 and an extension on said spring contacting with said lid only at the approximate center thereof, to yieldingly urge said lid uniformly against said journal box.

4. In a journal box having an opening 25 therein, a closure member therefor, a bolt pivotally securing one end of said lid to said journal box, a coiled spring around said bolt, said bolt being adjustable to permit adjustment of the tension of said spring, and an ex- 30 tension on said spring contacting with said lid only at the approximate center thereof, to yieldingly urge said lid uniformly against said journal box.

5. In a journal box having an opening 35 therein, a closure for said opening, a pivot bolt carried by the journal box and extending through the closure adjacent the periphery thereof and a single means applying tension to the closure forcing it into engagement with 40 the journal box, said means applying tension to the lid in surrounding relation to the bolt and at the center of the lid.

EDWARD GROVER DURNING.
